(57) **CLAIM**

The ornamental design for a playground apparatus, as shown and described.

DESCRIPTION

FIG. 1 is a perspective view of a playground apparatus;
FIG. 2 is a top plan view of the playground apparatus shown in FIG. 1;

FIG. 3 is a side plan view of the playground apparatus shown in FIG. 1;

FIG. 4 is a bottom plan view of the playground apparatus shown in FIG. 1; and,

FIG. 5 is an end plan view of the playground apparatus shown in FIG. 1.

The broken lines in FIGS. 1, 4 and 5 are for illustrative purposes only, are solely intended to show the environment in which the invention is used, and form no part of the claimed design.

The surface shading in FIGS. 1-5 is intended to show clearly the character and contour of all surfaces of the playground apparatus.
